UNITED STATES PATENT OFFICE.

GEORGE E. ALEXANDER, OF NEW YORK, N. Y., ASSIGNOR, BY MESNE ASSIGNMENTS,
TO A. LOWELL MFG. CO. INC., OF NEW YORK, N. Y.

CLOTHES-LINE HOLDER.

1,086,118.

Specification of Letters Patent.

Patented Feb. 3, 1914.

Application filed March 8, 1913. Serial No. 752,825.

To all whom it may concern:

Be it known that I, GEORGE E. ALEXANDER, a citizen of the United States, and a resident of the city, county, and State of New York, have invented certain new and useful Improvements in Clothes - Line Holders, of which the following is a specification.

The object of my invention is to provide a simple, durable and effective clothes line holder which will not get out of order, and which is especially adapted for indoor use. The desirable features of such a holder are that a considerable length of clothes line can be employed; that this line can be rolled up inside the holder when not in use, so as to be kept from dust, steam, and greasy vapors; that it shall unwind easily, and can be wound easily; that there shall be no parts which are liable to break or get out of order through carelessness or rough handling; and that the supporting fixtures when the line is in use, should be sufficiently strong to support the weighted lines. All of these advantages are comprised in my improved clothes line holder, one form of which is shown in the accompanying drawing in which:—

Figure 1 is a front elevation. Fig. 2 is a central longitudinal section. Fig. 3 is a central cross section. Fig. 4 is a detail of the reel spindle.

Same letters indicate similar parts in the different figures.

A, is the box casing, or shell preferably of metal and of cylindrical form, provided with supporting ears a, a, by means of which it is secured to the woodwork of the wall, or any other fixed support as desired. The body of this casing is provided at the front with a slot b, through which the clothes line passes, in winding and unwinding from the box. The ends of this box are removable; the end c, may be regarded as the head, and the end d, as the bottom of the box. These ends preferably lap over the body of the box, and are held in position by the spindle B, hereafter described; being provided with central apertures e, f, for that purpose.

C is a clothes line which, in boxes of usual

commercial and convenient size, will be about thirty-six feet long, but of course the 50 length of clothes line used, will depend upon the size of the reel box, in which it is to be found and kept.

One important feature of this device is the reel spindle B, which is preferably made 55 of a single piece of metal, cast or otherwise, and which comprises a somewhat slender shank g, with an eyelet opening h, through which the inner end of the clothes line is passed, and tied, an enlarged bearing i, 60 which engages the aperture in the head of the box, a handle j, on the outside of the head, and carrying if desired, a loosely pivoted knob k, by which it is grasped and turned. The spindle at the other end has a 65 bearing l, and emerges through the bottom of the box, where it is secured by a cotter pin m, or other convenient fastening means with a washer to serve as a bearing and draw-plate for the bottom of the box. A 70 ring n, or other convenient grasping means is secured on the outer end of the clothes line large enough to prevent its being drawn through the slot into the box.

In practical use, the whole or as much of 75 the clothes line as may be desired to use, is drawn out by the aid of the ring and passed over hooks, brackets, pins or other attaching means at various places of the laundry or other room in which the clothes are to be 80 hung.

I claim.

An improved clothes-line package consisting of a box of suitable shape with removable ends each having a central aperture, and 85 supporting ears whereby said box may be attached to a fixed support, a length of clothes-line coiled in said box, and a winding spindle located therein, provided with enlarged bearings to enter said apertures and 90 hold the parts of the said box together.

GEORGE E. ALEXANDER.
